STOP MOTION FOR TEXTILE APPARATUS

Walter J. Scott, Woonsocket, R. I.

Application January 9, 1936, Serial No. 58,290

13 Claims. (Cl. 118—4)

This invention relates to an improved stop motion for textile apparatus, more particularly for drawing frames; and has for one of its objects the provision of a simple and positive stop motion to act and stop the machine should the yarn break.

Another object of the invention is the provision of a stop motion which will act independently from any spring action and thus render the same positive in the result to be accomplished.

10 Another object of the invention is the provision of a stop motion which may be nicely adjusted so as to position the same at the desired location with reference to the travel of the yarn.

15 A further object of the invention is the provision of a stop motion which will act as a check to prevent improper tension on the yarn.

With these and other objects in view, the invention consists of certain novel features of construction, as will be more fully described, and 20 particularly pointed out in the appended claims.

In the accompanying drawings:

Fig. 1 is a front elevation of a fragmental portion of a drawing frame with my stop motion mounted thereon;

25 Fig. 2 is a sectional view through the structure shown in Figure 1;

Fig. 3 is a sectional view on a larger scale of the stop motion and its mounting bracket;

30 Fig. 4 is a sectional view substantially on line 4—4 of Figure 3, and showing in dotted lines the active position of the rockable actuating member in contacting position;

35 Fig. 5 is a diagrammatic view illustrating the electrical hookup for the stopping of the drawing frame;

Fig. 6 is a front elevation of a modified arrangement of my electrical connections and feeler member and also a modification with respect to the drawing frame upon which the same is 40 mounted;

Fig. 7 is a sectional view centrally through the supporting bracket shown in Figure 6.

In the drafting of wool the yarn frequently breaks between the delivery draft rolls and the 45 flier by means of which the same is packaged on a bobbin, and should a break occur of one of the ends in the frame, it is desirable that the frame be stopped until the broken ends are pieced together. I accordingly mount a stop motion on the frame adjacent the upper end of the flier so that should breakage occur between the draft rolls and the flier the frame will be stopped until the yarn ends are spliced together and proper tension placed on the yarn; and I 50 have so constructed my stop motion that it does

not depend on the use of springs nor is it materially influenced by different conditions under which it operates and thus is more positive in its operation than some other stop motions with which I am familiar; and the following is a more detailed description of the present embodiment of my invention, illustrating the preferred means by which these advantageous results may be accomplished.

With reference to the drawings, 10 and 11 represent a pair of nip rolls which receive the yarn 12 from the receiving rolls 13 and 14. A pair of delivery nip rolls 15 and 16 nip the yarn at 17 and draft or attenuate the yarn between this nip 17 and nip 18 of the rolls 10 and 11. 15 Carrier rolls 19 and 20 also 21 and 22 are positioned between the points of the nips but are not weighted and therefore have no drafting action upon the yarn. After drafting, the yarn now designated 23 passes into the top of the flier 24 emerging from the opening 25 and passing through guide 26 and along and about the arm 27 thence through the guide 28 and onto the bobbin 29 which rotates upon the spindle 30 and is 20 suitably traversed for the laying of the yarn 23 25 axially along its extent.

The flier bearing 24 is supported in the rail 31 and upon this rail I have mounted a bracket 32 by means of a bolt 33. On this bracket I have supported a U-shaped member 34 which is held 30 in position by a bolt 35 located in and through the slot 36 along which it may be adjusted to position the U-shaped support 34 as desired along its extent after which the head of the bolt 35 may be tightened to hold the same in place.

35 A rockable contact and feeler member 37 is pivotally mounted in the U-shaped support by means of a pair of bolts 38 having conical ends 39 to fit within the correspondingly shaped recesses 40 in the rockable member 37 for pivotally 40 mounting the rockable member therein. These bolts 38 are held in position by jam nuts 41 engaging the sides of the U-shaped member 34. A weight 42 is adjustably positioned on the member 37 and held in position by a lock screw 43 and 45 tends to swing the opposite feeler end 44 of the member 37 upwardly and into engagement with the travelling yarn between the nip 17 and its point of entrance into the hub of the flier. The engagement of the member 37 with the yarn prevents the weight 42 from swinging the member to its fullest extent and the arrangement is such that in operation the rockable member 37 when it engages the properly tensioned yarn will remain in substantially horizontal position. It will 50 55

be observed that the feeler member also exerts a tension on the yarn, which may be nicely adjusted.

Should the yarn break, or become slack to such an extent as to detrimentally affect the operation of the machine on the work, the rockable member 37 will swing into the dotted line position as shown in Figure 4, in which position its portion 44 on the feeler side of the pivot will be engaged and limited in its movement by the contact plate 45 which is insulated from the U-shaped support 34 by means of suitable insulated washers 46 and suitable insulation 47 about the holding screws 48 so as to complete the circuit and operate the stopping mechanism at some remote point of the machine.

For the electric circuit, I use one side of the machine as a ground while a live wire 49 is connected to the plate 45 insulated from the rest of the machine. A reference to Figure 5 shows a live wire 49 connected to the contact plate 45, while the machine will act as a ground to complete the circuit. In Figure 5, I illustrate a wire 50 leading to the transformer 51 to show this completion of the circuit. The transformer is connected to the line wires 52 and 53.

As the circuit is closed by the rockable member 37 engaging the contact plate 45, a magnet 54 is energized to cause a release of the latch 55 on the arm 56 carried by a lever 57 so as to permit the spring 58 to swing the lever 57 to the left in Figure 6 and move the rod 59 to cause a belt shifter 60 to shift the belt from the fast pulley 61 to the loose pulley 62 and thus remove the driving power from the drawing frame to permit it to stop.

In Figure 6, I have shown a gill box type of drawing frame with a vertical apron 65 about the upper of the front delivery rolls 66. As the yarn 67 is delivered from the rolls 66 and 68 it extends over the rockably mounted feeler and contact member 69 and thence to the flier 24, as previously set forth. This member 69 is pivoted as at 70 having an adjustable weight 71 tending 45 to swing the member 69 upwardly. A pivot mounting 72 is adjustable by means of the posts 73 in a socket 74 held in position by a set screw 75. At the contact end of the member 69 a portion 76 is raised for engagement with the resilient spring 50 member 77 mounted on the contact plate 78 to which the live wire 79 is connected. This spring is sufficiently resilient so as to permit movement of the spring to follow the feeler arm during any vibration which may be caused of the rockable 55 member 69 so that contact will be had for a sufficient length of time to cause the stop motion to act.

Where several of the ends are drafted side by side a single contact plate such as 78 may serve 60 for two rockable members, as shown in Figure 6, where they extend in opposite directions from their pivots as is clearly shown. Also, this arrangement permits of a horizontal mounting of the feeler member which in some instances has 65 its advantages for quicker action of the feeler arm should the yarn break.

The foregoing description is directed solely towards the construction illustrated, but I desire it to be understood that I reserve the privilege of 70 resorting to all the mechanical changes to which the device is susceptible, the invention being defined and limited only by the terms of the appended claims.

I claim:

75 1. In an electric stop motion for drawing

frames, a set of draft rolls, packaging means for the yarn, an electric circuit, a rockable feeler member in said circuit located intermediate said draft rolls and packaging means, said member being pivotally mounted at one side of the yarn and having an elongated finger extending transversely across the direction of travel of a stretch of yarn and laterally of the plane in which the yarn lies, the body of said finger being convex and positioned to engage the under side of the traveling yarn whereby the latter in passing thereover is caused to bear against a substantial arc of the circumference of the finger, an electrical contact arranged on the end portion of said finger and at the opposite side of the yarn from the pivotal mounting for the lever, a weight for urging said finger upwardly into engagement with the under side of the yarn, and a fixed contact in a position on the other side of the yarn to be engaged by the contact on said rockable member to 10 close the circuit and stop the machine upon 15 breakage of the yarn.

2. In an electric stop motion for drawing frames, a set of draft rolls, packaging means for the yarn, an electric circuit, a rockable feeler member in said circuit located intermediate between said draft rolls and packaging means, said member provided at one end with an electrical contact and having an elongated finger disposed under and extending transversely across the direction of travel of a stretch of yarn and laterally of the plane in which the yarn lies, the body of said finger being convex and positioned to engage one side of the traveling yarn whereby the latter in passing thereover is caused to bear against a substantial arc of the circumference of the finger, a weight at the other end portion of said feeler member for urging said finger into engagement with the yarn, and a fixed contact member arranged in a position on the other side 20 of the yarn as the weight to be engaged by the contact on said rockable member to close the circuit and stop the machine upon breakage of the 25 yarn.

3. In an electric stop motion for drawing frames, a set of draft rolls, packaging means for the yarn, an electric circuit, a rockable feeler member in said circuit located intermediate between said draft rolls and packaging means, said member comprising a rod provided at one end 30 with an electrical contact and extending transversely across the direction of travel of a stretch of yarn and laterally of the plane in which the yarn lies, the body of said rod being positioned to engage one side of the traveling yarn whereby the latter in passing thereover is caused to bear against a substantial arc of the circumference of the rod, a weight at the other end portion of said feeler member for urging said rod into engagement with the yarn, and a fixed contact 35 member arranged in a position on the other side of the yarn as the weight to be engaged by the contact on said rockable member to close the circuit and stop the machine upon breakage of the 40 yarn.

4. In an electric stop motion for textile machinery, a rockable contact feeler member adapted to normally engage a stretch of traveling yarn and having an intermediate portion extending across the line of travel of the latter and an electrical contact on the free end portion thereof, means for swingably mounting and supporting said member, means for urging said member into contact with the underside of the traveling yarn to tension the same, said member being limited 45

in its swinging movement upon engagement thereby, a fixed contact member on the opposite side of the yarn as the pivot mounting for the feeler member, and an electric circuit including machine stopping means closed by engagement of the contact on said rockable member with said fixed contact to actuate the latter means and stop the machine.

5. In an electric stop motion for textile machinery, drafting means, packaging means for the work, an electric circuit, a fixed contact member at one side of the yarn, a rockable feeler member extending laterally of the travel of the work and carrying a contact arranged on the same side 10 of the yarn as the fixed contact for engagement with said fixed contact on occurrence of breakage of the work, said feeler member being positioned to engage the work between said drafting and packaging means and to exert a predetermined tension on the work yet be blocked thereby from circuit closing engagement with said fixed contact when the work is properly tensioned, and means for urging said rockable member towards said fixed contact member.

25. 6. In an electric stop motion for textile machinery, a rockable feeler member adapted to normally engage a stretch of traveling yarn and having an electrical contact on an end portion, a pivot for said rockable member located intermediate of the ends of the latter, means on one side of said pivot for urging the yarn engaging portion of the member in the opposite direction on the other side of the pivot and move it laterally towards the yarn and into engagement with 30 the underside thereof to properly tension said traveling yarn to be limited only by the engaged yarn from further rocking movement, an electric circuit, and a fixed contact on the opposite side of said yarn as the weight and in a position to be 35 engaged by said rockable contact member should the yarn break or slacken a predetermined amount to close the circuit and stop the machine.

7. In an electric stop motion for textile machinery, a rockable feeler member provided with an electrical contact on an end portion, said feeler member being adapted to normally engage a stretch of traveling yarn and positioned below and at substantially right angles of the travel of the yarn, a pivot for said rockable member located intermediate of its ends, a weight on one portion of said member disposed from one side of said pivot for urging the yarn engaging portion of said member in an opposite generally upwardly direction on the other side of the pivot and move it into engagement with and exert a predetermined tension on said traveling yarn to be restrained from further rocking movement by the engaged yarn, an electric circuit, and a fixed contact on the opposite side of said yarn as the weight 50 and in a position to be engaged by said rockable contact member should the yarn break or slacken a predetermined amount to close the circuit and stop the machine.

8. In an electric stop motion for textile machinery, a rockable contact feeler member adapted to normally engage the underside of a stretch of traveling yarn, a bracket for pivotally mounting said rockable member, means for adjusting said pivot in said bracket, a weight adjustably mounted on said member for urging the same into engagement with one side of the traveling yarn and to exert a tension thereon, said member being limited in its swinging movement upon engagement thereby, a fixed contact member on the 75 opposite side of said yarn as the weight, and an

electric circuit including machine stopping means closed by contact of said rockable member with said fixed contact to stop the machine.

9. In an electric stop motion for textile machinery, a fixed electrical contact member positioned at one side of a moving stretch of yarn, an electric circuit, a feeler member electrically connected therewith and comprising an upwardly swingable arm normally arranged to extend transversely across the line of travel of the moving yarn, said feeler member having an intermediate portion over which the moving yarn passes and a free end portion adjacent to said fixed contact member and adapted to engage the latter upon abnormal run or breakage of the yarn 15 to close said electric circuit, pivot means for swingably mounting and supporting said arm, said pivot means being positioned on the other side of the yarn from said fixed contact and located between the yarn and the adjacent end of the 20 arm, and means adjacent to said pivot means and acting on said arm to urge the same into engagement with the underside of the yarn to tension the latter and also cause the arm to swing upwardly so that its free end will contact with 25 said fixed contact member to close the electric circuit and stop the machine upon breakage of the yarn.

10. In an electric stop motion for textile machinery, a fixed electrical contact member positioned at one side of a moving stretch of yarn, an electric circuit, a feeler member electrically connected therewith and comprising an upwardly swingable arm normally arranged to extend transversely across the line of travel of the moving yarn, said feeler member having an intermediate portion over which the moving yarn passes and a free end portion adjacent to said fixed contact member and adapted to engage the latter upon breakage of the yarn to close said 30 electric circuit, pivot means for swingably mounting and supporting said arm, said pivot means being positioned on the other side of the yarn from said fixed contact and located between the yarn and the adjacent end of the arm, and a 35 weight adjacent to said pivot means and acting on said arm to urge the same into engagement with the underside of the yarn to tension the latter and also cause the arm to swing upwardly so that its free end will contact with said fixed 40 contact member to close the electric circuit and stop the machine upon breakage of the yarn.

11. In a textile machine, in combination, a pair of delivery nip rolls, packaging means, supporting structure, a rockable feeler bar pivoted on 55 said structure and positioned between the pair of nip rolls and the packaging means and restrained from movement by engagement with the normal run of the yarn, the pivot axis of said bar extending in a direction substantially parallel to 60 the normal run of the yarn between the nip rolls and the packaging means, and means controlled by the movement of said bar upon abnormal run or failure of the yarn to stop the operation of the machine.

12. In a textile machine, in combination, a pair of delivery nip rolls, a flier, supporting structure, a rockable feeler bar pivoted on said structure and positioned between the pair of nip rolls and the top of the flier and restrained from movement by the normal run of the yarn, said bar extending transversely across the line of travel of the moving yarn and providing an intermediate 70 portion over which the yarn passes with a relative traversing movement, the pivot axis of said 75

bar extending in a direction parallel to the normal run of the yarn between the nip rolls and the flier, and means controlled by the movement of said bar to stop the operation of the machine upon abnormal run or failure of the yarn.

13. An electric stop motion device for textile machinery comprising a support, a fixed electrical contact member thereon, and a rockable feeler

bar over which the moving yarn passes, said bar being pivotally mounted on said support, the pivot axis of said bar being inclined from the horizontal and adapted to extend parallel with the normal run of the moving yarn as it passes over 5 the bar, and means tending to swing the bar against the yarn.

WALTER J. SCOTT.
